ATTORNEY

UNITED STATES PATENT OFFICE.

JAMES H. CARMEEAN, OF KANSAS CITY, MISSOURI.

HEATER.

Application filed August 13, 1928. Serial No. 299,389.

My invention relates to electric heaters and more particularly to circulation heaters in which a fan is provided for moving air over the heating element, the principal object of the invention being to simplify the construction and assembly of a heater of that character, to enclose and support a switch by heater-supporting elements, to adapt a guard for stabilizing the heater and retaining the switch and heating element, and to provide a compact unitary assembly comprising a relatively small number of parts.

In accomplishing these and other objects I have provided improved details of structure, the preferred forms of which are illustrated in the accompanying drawings, wherein:

Fig. 1 is a front elevation of a heater constructed according to my invention, the left half of the face plate being broken away to illustrate the mounting of the heating element and switch.

Fig. 2 is a longitudinal central vertical section of the device.

Fig. 3 is a perspective view of a fan member, heater member, screen, and face plate in separated position.

Referring in detail to the drawings: 30 1 designates a heater comprising a drum 2 having longitudinal internal grooves 3, and a heating element 4 including radial blades 5 slidably mounted in the grooves and coils 6 circularly arranged in openings 35 7 of the blades and supported thereby.

Leg plates 8 extend from the periphery of the drum and are preferably integral therewith and in parallel and spaced relation with each other, the front vertical edge 40 9 of the legs extending in the plane of the front end or edge 10 of the drum. The legs have feet 11 extending rearwardly parallel with the axis of the drum, and a shelf-like web 12 connects the legs and is located adjacent the lower end of the legs in spaced relation with the drum, to form therewith a switch-receiving chamber 13.

A switch 14 is adapted for positioning in the chamber with its face portion 15 projecting forwardly beyond the front end of the drum, and a housing-like bracket 16 adapted to fit into said chamber comprises a sheet of metal bent to conform to the size and shape of the legs and to provide laterally extending flanges or wings 17 to overlie the vertical edges of the legs, whereby

the bracket may be retained in engagement with the legs by a guard or face plate 18 presently particularly described. The drum is provided with an opening 19 to receive wires 20 extending from the switch for energizing the heating element.

The face plate 18 has a guard portion 21 provided with openings 22, the guard portion being preferably a ring-like member 65 and the openings being formed by bars 23 extending across the ring opening. The guard portion has a peripheral lug 24 adapted for engagement with a similar peripheral lug 25 on the front portion of the 70 drum, each lug having an opening to receive a fastening member such as a bolt 26.

The face plate further comprises a stabilizing and switch-retaining portion 27 having laterally extending wings 28 adapted 75 to project beyond the legs and feet of the drum-supporting structure, and an opening 29 for mounting the face plate over the front end of the switch, so that the face of the switch may lie substantially in the plane 80 of the plate. An annular boss 30 is provided on the plate around the opening for additional bearing area for the switch.

The stabilizing portion of the face plate is adapted to overlie the leg-engaging wings 85 of the switch housing bracket, and is secured to the legs by bolts 31 extending through openings 32 in the face plate and openings 33 in lateral lugs 34 of the legs.

A screen such as a wire disk 35 is mounted 90 in the front end of the drum and retained within the drum by the face plate when the latter is mounted as just described.

A fan 36 is mounted on a motor 37 and the motor is supported coaxially with the 95 heater on a boss 38 of a frame 39 having forwardly extending ears 40 adapted to overlie the periphery of the drum and attached thereto by bolts 41, the frame preferably supporting the fan within the drum 100 for driving a column of air over the heating element. A screen 42 is mounted in the rear end of the drum with its periphery retained between the frame and the drum.

A wire 43 leads from the switch to the 105 fan motor for controlling the fan.

The frame preferably includes a peripheral ring 44 adapted to overlie the rear end edge of the drum, for clamping the screen 42 to the drum, and the screen is preferably 110 supported in a ring 45 having an inwardly extending inner offset flange 46 forming a

shoulder 47 for engagement with the inner surface of the drum, the screen being attached to the outer face of said inner flange 46.

5. Attention is called to the position of drum openings 48 to receive the bolts 41, whereby the bolts extend into the drum in alignment with the horizontal blade 5^a of the heater, to serve as stop members for spacing the 10 heating element from the fan when the heating element is moved into position in the drum.

The parts being provided as described, it is apparent that a heating element may 15 easily be mounted in the drum, the switch attached to the bracket and the bracket positioned in the chamber. The face plate may then be attached to the drum and the supporting legs to retain the screen, guard 20 the front opening of the drum, support the switch bracket and retain it in firm engagement with the legs, and stabilize the drum in leg-supported position. The face plate provides a closure for the switch housing 25 and supports the front end of the switch. The fan frame may then be mounted on the drum and secured thereto, the suitable wire connections being assumed, and the entire device will comprise a portable unit which 30 may be positioned in any desired relation to an area to be heated.

What I claim and desire to secure by Letters Patent is:

1. In a heater, a drum, means supporting 35 the drum, a heating element mounted in the drum, a frame removably attached to one end of the drum for supporting a fan adjacent the heating element, and a guard plate removably attached to the other end of the 40 drum and having stabilizing portions engaged with the drum-supporting means.

2. In a heater, a drum having legs integral therewith and adapted for supporting the drum from a surface, a heating element 45 mounted in the drum, and a face plate having a guard portion engaged with the drum and a stabilizing portion engaged with the legs.

3. In a heater, a drum, legs having spaced 50 feet extending parallel with the axis of the drum for supporting the same, a heating element mounted in the drum, and a face plate comprising a guard portion removably attached to the drum and a stabilizing portion 55 extending at right angles to said feet and attached to the legs.

4. In a heater, a drum having spaced legs 60 extending from one edge thereof, a shelf connecting the legs and spaced from the drum to form a switch chamber, and a face plate removably attached to the drum to close one end thereof and overlying the legs to form a wall of said chamber, the plate 65 having an opening for communication with the chamber.

5. In a heater, a drum adapted to contain a heating element and having open ends and a conductor-receiving opening in its cylindrical wall, laterally spaced legs extending parallel with the axis of the drum, and a 70 switch chamber including a shelf extending between the legs in vertically spaced relation with the portion of the drum containing said conductor-receiving opening and providing for extension of a conductor from a switch to the heating element. 75

6. In a heater, a drum adapted to contain a heating element, and having open ends, laterally spaced legs attached to the periphery of the drum and having vertical front 80 edges aligned with the front end of the drum, a switch bracket having lateral wings adapted to overlie said vertical edges of the legs, and a face plate adapted to overlie the front end of the drum and for connection 85 with the legs to retain the bracket wings in engagement with the legs.

7. In a device of the character described including a drum and a screen, an annulus having an offset internal flange forming a 90 shoulder engageable with the inner surface of the drum for supporting the screen, and a frame including an annular ring for clamping the annulus to the end of the drum.

8. In a device of the character described 95 including a drum and a screen at one end of the drum, means for supporting the screen including an annulus adapted for engagement with the edge of said end of the drum and having an inwardly extending flange 100 offset to receive the screen, and a circular frame member engageable with the drum for clamping the annulus to the edge of the drum to retain the screen.

9. In a heater of the character described 105 including a switch and a drum having spaced legs, a shelf connecting the legs to form a switch chamber, and a face plate including a portion overlying the legs and connected therewith to form a wall of said 110 chamber.

10. In a heater, a drum having spaced legs extending from the periphery thereof, a shelf connecting the legs and spaced from the drum to form a switch chamber, and a 115 face plate removably attached to the drum and engaging the legs to form a wall of said chamber and having an opening for communication with the chamber.

11. In a heater, a drum having spaced 120 supporting legs, a bracket having wings adapted to overlie the legs, a guard plate adapted to overlie the wings for clamping the wings to the legs, and means for attaching the plate to the legs.

12. In a heater including a drum, a heating element in the drum, and a switch for controlling the heating element, a support including a leg connected to the drum, a switch bracket including a lateral wing 130

adapted to overlie the leg, and a face plate adapted to overlie the front end of the drum for clamping the bracket wing to the leg.

13. In a heater of the character described, 5 including a drum, a heating element slideable in the drum, and a fan, a removable frame for supporting the fan within the drum, and means for securing the frame to the drum including a member extending into 10 the drum for spacing the heating element from the fan.

14. In a heater of the character described, including a drum, a heating element slideable in the drum, and a fan, a frame for supporting the fan in fixed position at the 15 rear end of the drum including a ring having a forwardly extending ear, and means including a member adapted to stop the heating element for securing the ear to the drum. 20

In testimony whereof I affix my signature.
JAMES H. CARMEAN.
